UNITED STATES PATENT OFFICE.

JOHN C. HAAG AND EDWIN W. EVANS, OF NEW YORK, N. Y.

TUNNEL FOR CABLE RAILWAYS.

SPECIFICATION forming part of Letters Patent No. 355,448, dated January 4, 1887.

Application filed November 4, 1886. Serial No. 217,934. (No model.)

To all whom it may concern:

Be it known that we, JOHN C. HAAG and EDWIN W. EVANS, both of the city and county of New York, in the State of New York, have 5 invented a new and useful Improvement in Tunnels for Cable Railways, of which the following is a specification.

Our invention relates to railways in which the cars are drawn or propelled by means of 10 an endless cable or wire rope working in a tunnel arranged beneath the street-level between the track-rails, and in which the communication between the street-level and the tunnel is a narrow slot formed by two parallel slot-bars or bars of rolled iron secured at 15 a proper distance apart and in fixed relation to each other. In such railways the track-rails and the slot-bars are supported by cast or wrought metal yokes or frames, which are 20 arranged transversely to said rails and bars at a few feet apart. When the tunnel for the 25 cable and its supporting-pulleys has been constructed of masonry or of concrete it has been necessary to leave the trench or tunnel excavation open for a long time, in order to allow the 30 masonry or concrete a sufficient time to set or become thoroughly dry, and the street has therefore been obstructed for an inconveniently long time. To avoid such continued obstruction 35 of the street, it has been proposed to make the tunnel of planks or tiles of small size properly joined together, and also of previously-formed slabs of concrete of larger size than the tiles. The tunnel constructed of 40 wood would of course not be desirable, because of the perishable nature of the wood, and the construction of tiles and previously-formed slabs or sections of cement or concrete 45 is expensive, because of the labor involved in making and laying the tiles and in making the slabs or sections of cement or concrete, and because of the cost of the material used in 50 making such slabs or sections.

Our present invention consists in the combination, with the iron yokes or transverse frames for supporting the rails and slot-bars of a cable railway, of a cable-tunnel constructed of previously-molded sections or slabs of blast-furnace slag. Blast-furnace slag 55 is desirable as a material from which to form the tunnel slabs or sections for various reasons. It comprises iron as an ingredient in

large proportion, slag often having as much as thirty per cent. of iron in its composition, and hence when molded or cast into slabs or 55 sections and combined with the transverse yokes or frames, we provide, in connection with the iron yokes or frames, a tunnel structure which is itself largely composed of iron, and which is therefore of great strength. Al- 60 though attempts have been made to utilize blast-furnace slag for some purposes, no con- siderable quantity of it is used, and immense quantities of slag are produced every year as a waste product; hence the material itself is 65 far less expensive than cement or clay suit- able for forming tiles, and while in a molten state in the blast-furnace it may be run into suitably-constructed molds for receiving it, and thus without any material expense be cast 70 directly into slabs or sections of the proper size and shape to form a tunnel.

In the accompanying drawings, Figure 1 is a transverse section of a cable railway having a tunnel constructed according to our invention, and Fig. 2 is a horizontal section upon about the plane of the dotted line $x-x$, Fig. 1, showing two of the transverse yokes or frames which support the rails and slot-bars, and also showing the portion of the tunnel which is 80 between such yokes or frames and the end por- tions or sections which are on opposite sides thereof.

Similar letters of reference designate corre- 85 sponding parts in both figures.

A A designate the track-rails of the rail- way, and B B the two slot-bars, which extend parallel with each other and form between them the slot b, through which the tunnel C communicates with the street-surface. The 90 track-rails A and slot-bars B are secured to upright yokes or frames D, which are com- monly constructed of cast metal, and which are arranged transversely to the track-rails and slot-bars. The yokes or frames D are 95 supported upon suitable foundation-blocks, E, which may be of concrete or metal, and, as here shown, rest in chairs e, which provide for a slight movement of the yokes or frames at the top in a direction lengthwise of the rails 100 and slot-bars.

The tunnel C we construct of slabs or sec- tions of blast-furnace slag, which are previ- ous cast in molds to give them proper size

and shape. These slabs or sections may be of any desired size and shape, in order to form, when properly combined together, a tunnel, C, of suitable transverse section. In the present example of our invention the tunnel C is composed of slabs or sections C', which are curved or of segmental shape in their transverse section, and are of sufficient length to extend between the frames or yokes D. The slabs or sections C' each form one side of the tunnel, and are curved so that they converge to their lower edges, where they approach near to each other, and the space or opening between the lower edges of the sections C' 15 may be closed or sealed with asphalt, or other suitable cement.

As here represented, the yokes or frames D are formed with recesses, grooves, or channels d, of proper shape to receive the ends of the slabs or sections C', and said slabs or sections may be embedded in asphalt or other cement placed in the said channels or grooves d.

The cost of producing previously molded or cast slabs or sections of blast-furnace slag 25 suitable for the purpose will be less than the cost of producing such slabs or sections of

any other material of which we have knowledge. The tunnel constructed of such slabs or sections will be thoroughly water-proof and indestructible when buried in the ground, and by the use of slabs or sections composed of slag we provide, in connection with the iron transverse yokes or frames D, a tunnel structure which is itself largely composed of iron, and hence adds to the strength and rigidity of the railway structure.

What we claim as our invention, and desire to secure by Letters Patent, is—

The combination, with the iron yokes or transverse frames for supporting the rails and slot-bars of a cable railway, of a cable-tunnel constructed of previously-molded sections or slabs of blast-furnace slag, whereby there is produced, in connection with the said iron yokes or frames, a tunnel structure which is 45 itself largely composed of iron, substantially as herein described.

JOHN C. HAAG.
EDWIN W. EVANS.
